UNITED STATES PATENT OFFICE.

DAVID S. WOOD, OF MEDFORD, OREGON.

STOOL.

1,242,407.

Specification of Letters Patent.

Patented Oct. 9, 1917.

Application filed August 31, 1915. Serial No. 48,268.

To all whom it may concern:

Be it known that I, DAVID S. WOOD, a citizen of the United States, residing at Medford, in the county of Jackson and

5 State of Oregon, have invented certain new and useful Improvements in Stools, of which the following is a specification.

This invention has relation to certain new and useful improvements in stools, and 10 has for its primary object to provide a folding stool of the type known as counter stools,

The invention has for another object, the provision of a stool which will be of such construction that two of the supporting legs 15 thereof may be readily folded against the remaining supporting leg and the entire stool swung to rest position beneath a counter or the like.

The invention has for another object, the 20 provision of a stool which will be of simple and durable construction and which when not in use may be readily swung to position adjacent the front of a counter, or the like, where it will be out of the way and utilize 25 the minimum amount of space.

The invention has for a further object, the provision of a folding stool of the above 30 stated character which will be of such construction that the main supporting leg thereof may be hinged or otherwise secured to the floor and the remaining leg hinged to the seat swung to rest position against the main supporting leg so that all of the 35 supporting legs may be in upright position beneath the seat when the stool is not in use.

A still further object of the invention resides in the provision of a stool of the above 40 stated character which will be of improved and simplified construction and in which will be included a spring actuated trigger which will serve the double purpose of forcing the hinged supporting legs to their outermost positions as the stool is opened up and also assist in returning the supporting 45 legs and stool to rest position after use of the stool.

With the above and other objects in view, the invention resides in the novel construction, combination, and arrangement of parts 50 as hereinafter set forth in the specification, pointed out in the claims and shown in the accompanying drawings, in which—

Figure 1 is an elevation of my improved stool in position for use in front of a conventional form of counter, the counter and

a portion of the floor being shown in section.

Fig. 2 is an elevation at right angles to Fig. 1 and looking toward the counter.

Fig. 3 is a view similar to Fig. 1 with the 60 stool in rest position.

Fig. 4 is an elevation of the stool, looking at the rear side thereof; and

Fig. 5 is a longitudinal vertical section through the main supporting leg and spring 65 actuated trigger.

Referring to the drawings in which similar reference characters designate corresponding parts throughout the several views, 1 designates the main supporting leg 70 of the stool, which is hinged at its lower end, as shown at 2, to a floor or other support 3 in front of a counter 4 or adjacent a wall or table as desired, the main supporting leg 1 when in normal or upright 75 position serving to support the seat 5 beneath the extended edge 6 of the counter 4, as clearly shown in Fig. 3. It will be understood that the seat 5 is rigidly secured upon the inclined upper end 7 of the main 80 supporting standard 1 and this main supporting standard 1 has a transverse foot piece 8 secured to its rear edge and extending to either side to receive the feet of a person positioned upon the seat 5 when the 85 stool is opened up or swung out from under the extended edge 6, as shown in Fig. 1.

When the stool is opened up for use, as shown in Figs. 1, 2 and 4, the seat 5 is in horizontal position outward of the extended 90 edge 6 of the counter 4 and is securely supported in this position by the main supporting leg and the remaining supporting legs 9 which are hinged at their upper ends, as shown at 10, to the under face of the seat 95 5 and have their lower ends resting upon the floor or other support 3 when the stool is opened up for use, it being understood that the supporting legs 9 are somewhat shorter than the main supporting leg 1 and 100 will therefore rise from engagement with the floor or other support 3 and swing to position against the main supporting leg 1 as the latter returns to upright position after use of the stool. It will be also understood that the supporting legs 9 are connected adjacent their upper and lower ends by suitable cross pieces 11, said connecting cross pieces 11 serving to limit swinging movement of the supporting legs 9 toward 110

the main supporting leg 1, while the flat upper and lower ends of the supporting legs 9 limit outward swinging movement of the same.

5 The main supporting leg 1 has a longitudinal channel 12 in its inner face within which is slidably engaged the spring actuated trigger 13 which will now be clearly described. The spring actuated trigger 13 10 has an enlarged rounded lower end 14 which rests upon the floor or other support 3 and a curved upper end 15 which moves outwardly and engages the upper cross piece 11 and forces the same away from the main 15 supporting leg 1, thereby causing the supporting legs 9 to swing outwardly to the position shown in Fig. 1, as the main supporting leg 1 is swung upon its lower hinged end to withdraw the seat 5 from beneath 20 the extended edge 6 of the counter 4.

The spring actuated trigger 13 is connected with the main supporting leg 1 by a suitable guide pin 16 carried by said main supporting leg 1 and projecting through the 25 longitudinal channel 12 and through the elongated longitudinal guide slot 17 in the spring actuated trigger 13, adjacent the central portion thereof, the helical spring 18 within said guide slot 17 having one end 30 resting in the socket 19 formed in the lower end of said guide slot 17 while the opposite end of said spring 18 is engaged around a pin 20 projecting laterally from the guide pin 16. It will therefore be seen that the 35 spring 18 will serve to resiliently retain the spring actuated trigger in inoperative position and will also act to return said trigger to this position, clearly shown in Fig. 5, as the main supporting leg 1 is returned to up- 40 right position after use of the stool.

It will also be seen that the guide pin 16 serves to guide the spring actuated trigger 13 in the channel 12 during movement of the main supporting leg 1 in either direction.

45 From the foregoing, it will be seen that I have provided a stool of improved and simplified construction and which will be durable as well as efficient in use, and may be used as a lunch counter stool as illustrated or may be secured to a movable base and used in assembly halls, schools, and many other places.

While the preferred embodiments of the invention have been clearly shown, it will 55 be understood that minor changes in the details of construction and arrangement of parts may be resorted to within the scope of the appended claims without departing from the spirit of the invention or sacrificing any of the advantages of the same.

What is claimed is:

1. A stool comprising a main supporting

leg hinged to the floor, a seat secured upon said main supporting leg, additional supporting legs connected and hinged to the 65 seat, and means slidably longitudinally upon the main leg and maintained at one end in contact with the floor for forcing, by reason of such contact, said means against the additional legs for swinging them away 70 from the main supporting leg to assist in sustaining the seat when the stool is swung into position for use.

2. A stool comprising a main supporting leg hinged to the floor, a seat rigid on said 75 hinged supporting leg, supplemental supporting legs hinged to said seat, and a member slidably longitudinally on said main supporting leg with one end maintained in contact with the floor and movable on said 80 leg by reason of such contact when the leg is swung into position for use, said sliding means engaging the supplemental legs and swinging them into position to assist in supporting the seat.

85 3. A stool comprising a hinged main supporting leg having an inclined upper end and a foot rest adjacent its lower end, a seat secured upon said inclined upper end, additional supporting legs hinged to the under 90 face of said seat adjacent the main supporting leg, said additional supporting legs being connected, said main supporting leg having a channel formed therein, a trigger 95 slidably engaged in said channel and having one end engaged with the support to which the main supporting leg is hinged, the opposite end of said trigger being adapted to force the additional supporting legs away from the main supporting leg, and means for guiding said trigger within said 100 channel and resiliently retaining said trigger in normal position.

4. A stool comprising a main supporting leg adapted to be hinged to a permanent 105 support, a seat secured at an incline to the upper end of said main supporting leg, additional supporting legs hinged to said seat and adapted for limited outward swinging movement during tilting of the main 110 supporting leg, a trigger within said main supporting leg for forcing said additional legs away from said main supporting leg, means for connecting said trigger with said main leg, means for resiliently retaining 115 said trigger in one position, and a foot rest carried by said main supporting leg.

In testimony whereof I affix my signature in presence of two witnesses.

DAVID S. WOOD.
